AUGUSTE POIREL, OF NEW YORK, N. Y., ASSIGNOR TO HIMSELF AND
PIERRE BERNARD, OF SAME PLACE.

Letters Patent No. 73,832, dated January 28, 1868.

IMPROVEMENT IN BOILER-SCRAPERS.

The Schedule referred to in these Letters Patent and making part of the same.

TO ALL WHOM IT MAY CONCERN:

Be it known that I, AUGUSTE POIREL, of the city, county, and State of New York, have invented a new and improved Boiler-Scraper; and I do hereby declare that the following is a full, clear, and exact description thereof, which will enable others skilled in the art to make and use the same.

Figure 1 represents a side elevation, partially in section, of my improved boiler-scraper.

Figure 2 is a transverse section of the same, the plane of section being indicated by the line $z z$, fig. 1.

Similar letters of reference indicate corresponding parts.

This invention relates to a new device for cleaning boiler-tubes, and consists in arranging a series of disks upon a straight bar, said disks being held at suitable distances apart by means of washers interposed between them.

The diameter of the end disk which first enters the tube is smaller than that of the tube, and the diameter of the next disk is somewhat larger than that of the first, and thus the disks gradually become larger toward the handle, until the diameter of the tube is reached. Thence the disks again become smaller toward the handle. The object of these graduations in the size of the disks is to give each disk a share of the work. The first disk clears the tube of a small layer of incrustation, the second takes off another layer, and so forth, until the largest disk clears the whole interior of the tube. If the disks had all the same diameter as the tube, the first disk would meet with such resistance that the device could not be pushed through the tube. The diminishing of the disks from the largest disk towards the handle is not absolutely necessary, but is advisable, for the purpose of facilitating the withdrawal of the scraper from the tube, and to allow the removal of any impurities that might have remained in the tube behind the scraper.

The invention also consists in perforating some of the disks, so that they may be elastic, to make them yield to inequalities in the inner side of the tube.

A represents a straight rod, having a fixed shoulder, α , near one end, and a screw-thread upon each end.

B B^1 B^2 , &c., are a series of annular disks, fitted upon the rod A, and C C^1 C^2 , &c., are washers, drawn upon the rod A, and interposed between the disks B, as shown. The disk B is placed upon the rod A, against the shoulder α , then the washer C is put on, then the disk B^1 , washer C^1 , and so forth, until the last disk, B^5 , or the last washer, is held in position by means of a nut or headed screw, b, as shown. The front disk, B^5 , is smaller in diameter than the next disk, B^4 , and this is smaller again than the disk B^3 , the disk B^2 being the largest, and of equal diameter with the tube to be cleaned. The disk B^1 is again smaller than B^2 , and B is still smaller than B^1 , as is clearly shown in fig. 1, and for the purpose above set forth.

The disks can be easily removed and replaced by others, so that the device can be adapted to tubes of various diameters. The largest disk B^2 may be perforated, as shown in fig. 2, so as to be elastic, to yield to the inequalities in the interior of the tube. The rod A is screwed or otherwise fastened to a suitable handle D, as shown. The number of disks may be varied at pleasure.

I do not claim broadly the disks, nor the method herein described of attaching them to the rod, as I am aware that this is not new; but having thus described my invention,

What I claim as new, and desire to secure by Letters Patent, is—

1. The construction of the metallic scraping-disks, of unequal diameters, arranged upon the same rod, whereby each disk will perform a portion of the work without permitting the front disk alone to scrape the tube, as herein shown and described.

2. The construction of the metallic disks, with perforations, to give them elasticity, whereby obstructions in the tube will not prevent the operation of the scraper, as herein shown and described.
